CLAIM

The ornamental design for a change counting machine, substantially as shown and described.

DESCRIPTION

FIG. 1 is a top and right front perspective view of a change counting machine showing our new design; FIG. 2 is a top plan view thereof; FIG. 3 is a right side elevational view thereof; FIG. 4 is a left side elevational view thereof; FIG. 5 is a rear elevational view thereof; FIG. 6 is a front elevational view thereof; FIG. 7 is a bottom plan view thereof; FIG. 8 is a top and left front perspective view of another embodiment of our new design of FIGS. 1-7 wherein a cover and carrying handle have been added thereto, all other views being substantially similar to those visible in FIGS. 1-7.

FIG. 1**FIG. 2****FIG. 3****FIG. 4****FIG. 5****FIG. 6****FIG. 7****FIG. 8**
